UNITED STATES PATENT OFFICE.

GEORG GEYER, OF BERLIN, GERMANY.

WATER-MOTOR FOR UTILIZING THE EBB AND FLOW OF THE TIDE.

No. 821,480.

Specification of Letters Patent.

Patented May 22, 1906.

Application filed December 21, 1905. Serial No. 292,846.

To all whom it may concern:

Be it known that I, GEORG GEYER, a subject of the German Emperor, and a resident of Berlin, Germany, have invented certain new and useful Improvements in Water-Motors for Utilizing the Ebb and Flow of the Tide, of which the following is a specification.

This invention relates to water-motors of that kind in which the ebb and flow of the tide are utilized for obtaining driving power, for which purpose there is provided in a back-water reservoir a turbine, the working of which depends on the rising and falling of the level of the water in the reservoir, and this reservoir has an outlet into a lower-situated reservoir with a lower water-level, and the power produced by the water rushing in is transmitted to the place where it is to be applied by the usual means.

The essential feature of the invention consists therein that the piston of a water-pressure cylinder is used for carrying the turbine. The flowing in and flowing out of the water in the cylinder is regulated by a float in front of the turbine in accordance with the level of the water in the back-water reservoir for the ebb-water, which float is constantly followed by the turbine by means of a screw-thread or the like provided on a telescoping rod rigidly connected with the plug of the regulating-cock of the water-pressure cylinder, and the flow is regulated in a manner that the turbine only very gradually rises and sinks according to the gradual rising and sinking of the water-level.

Figure 1 shows the whole plant in a side view and partly in section. Fig. 2 shows a horizontal section through the same. Figs. 3 and 4 are detail views. Figs. 5 to 7 show the regulating-cock in a horizontal section with different positions of the plug.

Similar letters refer to similar parts throughout the several views.

a and *b* are the reservoirs separated from each other, of which the one *a*, when the tide commences, is protected in the well-known manner against the inrush of the water by the automatically-closing valves *c* or the like, while the tide-water is conducted to the reservoir *b* through the valves *d* opening into the same. The water will consequently stand higher in the reservoir *b* than in the reservoir *a*, so that the water-wheel of a turbine *g*, likewise arranged in a manner already known between the two reservoirs fed by water from the reservoir *b*, is put into rota-

tion by the water rushing out of the same, and this movement can by a suitable transmitting mechanism be converted into driving power for any technical purposes. 60

For supporting and for lowering and raising the turbine *g* in accordance with the constantly-changing level of the back water the piston *f* of a water-pressure cylinder moved by a forcing-pump (not shown in the drawings) is used, whose movement is automatically regulated by the following device. On the guide-frame *w*, which rigidly connects the piston-rod of the piston *f* with the turbine *g*, is rigidly fastened an arm *l*, extending into the reservoir *b*, in which there is guided a rod connected with the float *u*, and can be moved up and down, but not be turned in the same. To the lower end of this rod is rigidly connected the slide *v*, which 70 encompasses at its upper end, where it is provided with a screw-thread, a rod *t*, fastened with its upper end to the arm *l* turnably, but not slidably, which rod can be lengthened and shortened after the manner of a telescope. The rod *t*, whose two sliding parts cannot be turned one on the other, owing to the arrangement that a projection on the one part engages a slit in the other in a manner already known and which will therefore not 80 be described here, so that on the one part being turned the other is turned likewise. This rod *t*, made water-tight, passes through the bottom of the reservoir *b* and out of the same at *r*. The lower end of the rod *t* is rigidly 85 connected to the plug of the three-way cock *n*, provided between the water-pressure cylinder and the forcing-pump. From this three-way cock leads the way *o* to the forcing-pump, the way *q* to the space below the 90 piston *f* of the water-pressure cylinder, and the way *p* to the water-reservoir of the forcing-pump or to any other outlet. 95

The working of this plant is as follows: On the flood coming in the float *u* commences to rise a little and to move ahead of the turbine. As the arm *l* prevents it from moving sidewise and it can thus only rise vertically and as, further, the slide *v* is rigidly connected to the rod of the float and is guided on the rod *t* or the thread *s*, so that it likewise cannot move out of the way, but must, the same as the float, ascend exactly perpendicularly, it must act on the screw-thread *s* of the rod *t* in a manner that it will turn, by means of the screw-thread, the upper as well as the lower part of the rod *t* and both in the same direc- 105 110

tion, as these parts cannot turn one upon the other. By this turning of the rod *t*, which is preferably so calculated that, in consequence of a corresponding slant of the screw-thread, it is forty-five degrees, the three-way plug of the cock *n* is turned in the direction of the arrow 1, Fig. 5, and gets into the position Fig. 6, whereby there is established a communication between the way *o*, coming from the forcing-pump, and the way *q*, leading to the water-pressure cylinder. In consequence of this the turbine *g* is raised a little by the water coming from the forcing-pump through the plug of the cock and the way *q* and acting on the piston *f*, so that the turbine follows the float, and the height of the fall becomes equalized again. In order to allow of this upward movement of the turbine, it must be possible to lengthen the rod *t*; but in order that the water should not act any further after this upward movement of the same and press it above the level of the water provision has been made in the present invention that the cock *n* is at once closed again when the turbine has moved upward only a small step of its whole upward movement, and so on after each small upward movement. This is again effected by the screw-thread *s* of the rod *t*, for if during the short upward movement of the turbine also the upper part of the rod *t*, which is turnably connected with the arm *l*, is raised the rod *t* is turned by the screw-thread *s* in the opposite direction, as this thread must wind its way through the slide *v*, which is rigidly connected to the float *u*, and the float cannot yield. In consequence of this the lower part of the rod *t* turns the plug of the cock *n* out of the position shown in Fig. 6 in the direction of the arrow 2 back into the position shown in Fig. 5—that is to say, it blocks the way of the pressure fluid to the pressure-piston *f*, so that the turbine cannot be raised any further and not be driven above the level of the water. The just-described processes are repeated in succession during the tide. If now the ebb follows, the float *u* sinks. It is to be presumed here that the slide *v* when the tide is highest has its position about in the middle of the screw-thread *s*, which corresponds with the checking position of the plug of the cock *n*. (Shown in Fig. 5.) If now the float sinks, its slide *v* turns the rod *t* with the co-operation of its screw-thread in a manner that the plug of the cock *n* is turned in the direction of the arrows 3 (shown in Fig. 5) and into the position shown in Fig. 7, whereby there is established a communication between the water-pressure cylinder through the tube *q* with the tube *p* for the pressure-water, so that a certain part of the water below the

piston passes out, and the turbine sinks a corresponding distance; but as the float *u* does not sink so rapidly, and consequently also the slide *v*, rigidly connected to the float *u*, does not change its position quite as rapidly as the turbine, the screw-thread *s* of the rod *t* on the latter being shortened must wind itself again through the slide *v* in the opposite direction back to its previous position; but in doing so it turns the rod *t* in a manner that the plug is turned again out of the position shown in Fig. 7 in the direction of the arrow 4 back into the position shown in Fig. 5, and thereby stops the flowing out of the pressure-water from the water-pressure cylinder in order that the same does not become quite empty, in consequence of which the turbine would sink in a moment, or at least much too rapidly, which might damage and throw out of order the whole installation. The rising as well as the sinking of the turbine is therefore effected only gradually, or by steps, so that when the float sinks only a little the cock is opened only so far that but a small quantity of water can run out, whereupon on the subsequent sinking of the turbine, however small it may be, the cock for stopping the exit of the pressure-water is at once closed, which process is repeated step by step until the turbine has reached its lowest position.

What I claim as my invention, and desire to secure by United States Letters Patent, is—

1. In a tidal motor, the combination with two reservoirs, of a rising and falling turbine arranged between the reservoirs, and an automatically-controlled pressure-operated device for raising and lowering the turbine in harmony with the changing level of the water.

2. In a tidal motor, the combination with two reservoirs, of a rising and falling turbine arranged between the reservoirs, a pressure-operated device for raising and lowering the turbine, and an automatic controlling-valve device including a float located in one of the reservoirs.

3. In a tidal motor, the combination with two reservoirs, of a rising and falling turbine, a fluid-pressure cylinder and piston operatively related to the turbine for raising and lowering the same, a valve for said cylinder and a valve-operating mechanism including a valve-operating rod, and a float carried with the turbine-support and operatively engaging said rod for turning the same.

In witness whereof I have hereunto set my hand in presence of two witnesses.

GEORG GEYER.
